UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

PILE-DRIVER ATTACHMENT FOR ROCK DRILLS.

Application filed February 20, 1926. Serial No. 89,755.

This invention relates to pile drivers, but more particularly to a pile driver attachment for fluid actuated rock drills of the hammer type in which the driving block is 5 of considerably smaller cross sectional area than the space in which it reciprocates.

One object of the invention is to enable the driving block to adjust its position in the attachment so that the fullest possible 10 contact between the driving block and the end of a pile may be obtained during the driving operation, irrespective of any relative tilting between the pile and the attachment.

15 Other objects will be in part obvious and in part pointed out hereinafter.

The invention consists of the combinations of elements and arrangement of parts having the general mode of operation substantially as hereinafter described and more 20 particularly pointed out in the appended claims and illustrated in the accompanying drawings, in which

Figure 1 is an elevation, partly in section, 25 of the front end of a rock drill equipped with a pile driver attachment constructed in accordance with the practice of the invention, taken on the line 1—1 of Figure 2 looking in the direction of the arrows, and

30 Figure 2 is an elevation in section of the attachment taken through Figure 1 on the line 2—2.

Referring to the drawings, the invention is shown embodied in a fluid actuated hammer type rock drill in which a cylinder A is provided with a reciprocating hammer piston B, only the front end of which is shown. A front cylinder washer C seals the front end of the cylinder and is bored to receive 40 slidably an anvil block D. In this instance, the front cylinder washer C is provided with a reduced forward extension E for centralizing an attachment or front head F secured to the cylinder by suitable side bolts 45 G arranged on opposite sides of the drill for clamping together the various parts which comprise the casing of the drill.

In accordance with the practice of the invention, the attachment or front head F carries at its forward end a pair of parallel projections or walls H and J. The walls H and J are preferably spaced at equal distances from the longitudinal axis of the rock drill to form a space K therebetween 55 into which space may be inserted a pile L

or other similar article to be driven. Within the space K is arranged a striking block O having a flat forward surface P adapted to rest on the end of the pile L. The striking block O is preferably of a rectangular cross sectional area and has rearwardly inclined tapered surfaces Q and R which terminate at their small ends in a slight projection S against which the blows of the anvil block D may be delivered. The surface T of the projection S against which the blows of the anvil block D are delivered is preferably of spherical form so that a good contact may be at all times obtained between the anvil block and the surface T in 70 any position which the striking block O may assume in the space K.

Suitable means are provided for limiting the forward travel of the striking block O in the space K. To that end cheek plates U are secured on opposite ends of the inner surface of the wall H and in the present instance the cheek plates are clamped firmly to said wall by means of suitable bolts V and nuts W. In order to protect the bolts 80 V against injury which might otherwise be caused by the blows of the striking block against the cheek plates, tongues X are formed on the cheek plates to extend into suitable grooves Y formed in the wall H. 85

To the end that transverse movement of the striking block O may be limited, the cheek plates U are provided with upwardly extending projections Z. The projections Z are so spaced with respect to each other 90 that there is sufficient room for the striking block to tilt from the longitudinal axis of the attachment within limits without binding or catching on the projections.

In the usual type of pile driving devices 95 heretofore in use, considerable difficulty has been experienced in maintaining a full contact between the striking block and the end of the pile. This is due chiefly to the fact that considerable clearance usually exists 100 between the guiding means of the attachment, such as the walls, or walls and cheek plates as in the present invention, and the pile. The extreme vibration set up during 105 operation of the machine tends to tilt the machine with respect to the pile and if the striking block is so held within the attachment that it is unable to adjust its position with respect to the pile, the blows may be delivered to one corner or one edge of the 110

pile. After a repeated number of blows have been delivered to one corner, a slanting surface will be formed on the end of the pile and thereafter it will be difficult to drive the pile in the required direction. By means of the present invention this objectionable feature has been entirely eliminated, since the striking block may at all times adjust its position with respect to the end of the pile regardless of any relative tilting which may take place between the pile and the attachment.

I claim:

1. The combination with a fluid actuated rock drill having a cylinder and a reciprocating piston in the cylinder, of a front head having parallel walls, a driving block arranged loosely between the walls, cheek plates supported by one of the walls to engage a pile and to prevent ejection of the driving block from the front head, and means on the cheek plates to limit transverse movement of the driving block.

2. The combination with a fluid actuated rock drill having a cylinder and a reciprocating piston in the cylinder, of a front head having parallel walls at its side to form a space therebetween, a driving block between said walls and of smaller width than

the space to permit the striking block to tilt with respect to the longitudinal axis of the front head, cheek plates secured to one of the walls for preventing ejection of the driving block from the front head, and upwardly extending projections carried by the cheek plates to limit transverse movement of the driving block.

3. The combination with a fluid actuated rock drill having a cylinder and a reciprocating hammer piston in the cylinder, of a front head having parallel walls at its side to form a space therebetween, a rectangular driving block reciprocable between said walls and of smaller width than the space to permit tilting of the driving block with respect to the hammer piston, cheek plates on one of the walls to retain the striking block in the front head, upwardly extending projections on the cheek plates to limit transverse movement of the striking block, means for securing the cheek plates in position, a groove in one wall, and tongues on the cheek plates to cooperate with the groove for protecting the securing means against the blows of the striking block.

In testimony whereof I have signed this specification.

CHARLES C. HANSEN.
